UNITED STATES PATENT OFFICE.

FREDERICK B. COOK, OF NEW YORK, N. Y.

MAIL-CHUTE.

1,338,976.

Specification of Letters Patent.

Patented May 4, 1920.

Application filed May 15, 1915, Serial No. 28,347. Renewed December 8, 1917. Serial No. 206,328.

To all whom it may concern:

Be it known that I, FREDERICK B. COOK, a citizen of the United States, and a resident of the borough of Manhattan, in the city, county, and State of New York, have invented certain new and useful Improvements in Mail-Chutes, of which the following is a specification.

This invention relates to improvements in and relating to mail chutes, and has for its object to provide a chute which will be free from obstructions that may impede or choke the passage of mail therethrough, and which may be readily disassembled by authorized persons to enable the same to be repaired or to remove any mail matter that should be caught therein, and to provide such a chute which is more efficient than such mail chutes previously in use.

More particularly, an important object of my invention is the provision of a letter-tight joint between the box or body of the chute and the front or panel, so as to prevent any letters or like mail matter from lodging or sticking in the joint.

With these and other objects in view, one embodiment of my invention is shown in the accompanying drawings, and will be hereinafter more fully described and the invention will be finally pointed out in the claims.

In the drawings,

Figure 1 is a front elevation of one embodiment of my improved chute;

Fig. 2 is a front elevation of the same with the front walls removed;

Fig. 3 is a rear elevation of the front walls and locking bar;

Fig. 4 is a vertical central section of the upper portion of my said embodiment of improved chute;

Fig. 5 is a vertical central section of the intermediate portion thereof;

Fig. 6 is a vertical central section of the bottom portion of the same;

Fig. 7 is a vertical section of jamb with front wall attached;

Fig. 8 is a detail of the drop-opening gate;

Fig. 9 is a cross-section on the line *a—a* of Fig. 1;

Fig. 10 is a cross-section on the line *b—b* of Fig. 1; and

Fig. 11 is a cross-section on the line *c—c* of Fig. 1.

Similar reference characters indicate cor-

responding parts throughout the several views.

Referring to the drawings, and more particularly to Figs. 2 and 9 thereof, a continuous channel comprising a rear portion 60 and side portions 11 and 12 bent forwardly at right angles therefrom and having a slight resiliency, is supported in position by straps 13 arranged at intervals along the height of the same, and attaching strips 14 and 15 extending along the height of the chute and secured at each side of the said straps. At the forward or outer portions the said side walls are turned inwardly at right angles thereto, forwardly 65 therefrom for a bend slightly greater than 90°, outwardly in a line parallel with the said inwardly bent portion, and backwardly at right angles to the said outwardly bent portion, and extending to the said inwardly bent portion at a point removed from the said side walls, thereby forming hollow jambs 16 and 17 at each side of the channel having a slight resiliency, together with the side members 11 and 12, and having flat 70 front faces, inclined inner faces, and longitudinal recesses at the sides thereof extending along the height of the chute. At the upper end of the said channel is provided a hopper 19 having its lower end extending 75 into the upper end of the said channel, and having its forward face 20 inclined outwardly to form a suitable unobstructed connection with the next chute section of the floor above. A top section 21 extends 80 around the front and sides of the said hopper, and has the rear or inner portions 22 of the sides bent inwardly upon the rear face thereof. The upper edges of the said hopper are bent over upon the upper edge 85 of the top piece, as at 23, and the sides of the said top piece are provided with depending portions 24 for securing the same to the upper end of the next chute section below.

To this purpose, the lower portions of the depending portions 24 are folded upon themselves, as at 25, and the forwardly projecting ends 26 of a bar 27 extending across the back of the chute, beneath longitudinal strips 14 and 15, engage the said folded portion and securely hold the same to the upper edge of the chute section by means of screws 28 passing therethrough. The portion of the said bar 27 between the strips 14 110

and 15 is spaced from the chute for permitting the same to be secured to the wall. Blocks 29 are screwed to the said depending portions, and molding pieces 30 are soldered 5 thereon to cover the joint between the top piece and the continuous channel. A cornice 31 is provided at the upper portion of the top piece and is secured thereto by means of screws 32 passing through the ends 10 of a bar 33 at the back of the same.

A base 34 is provided at the lower end of the said channel, extending around the front and sides of the same, and provided at the back with angular attaching members secured 15 to the sides of the base at 35, and extending beneath the strips 14 and 15 at the rear. A frame 36 is provided at the upper edge of the said base, and is provided with a downwardly depending flange 37. A rectangular 20 tube extension 38 is provided at the lower end of the said channel, which is adapted to extend into the hopper of the next lower chute section, having its rear face engaging at its upper portion the rear of the 25 said channel and the upper portions of the front and side faces bent upon the said frame 36, as at 38', Fig. 6. The said bent-over portions of the sides are secured to the sides of the frame by means of molding 30 pieces 39, which are secured to blocks 40 provided at the lower ends of the said channel. The frame 36 is provided beneath the jambs of the channel with struck-up 35 projections 41, which extend into the ends of the said jambs, and thereby reinforce the same.

The front wall completes the mail chute, and each section of the said chute is provided with a plate glass panel 42, so as to enable 40 an observer to see whether or not letters dropped therein fall, and whether the chute is clogged. The frame of the front wall comprises metal strips 43 and 44 at the sides, of substantially U-shape in cross-section, but having the inner leg of the U shorter than the other, and provided with a flanged portion 45 projecting inwardly at right angles therefrom, and is inclosed within a sheet-metal shell 46, which is bent over 45 the edge of the outer portion of the said strip, and extends upwardly from the inner portion to form a channel 47 to receive the edge of the plate glass panel 42. The base of the said channel 47, that is to say, the channel wall 50 facing the jamb, is inclined in a direction away from the inclined wall of the jamb, the two inclined walls converging toward the interior of the chute. Thus, when the front or glass panel is in place, there will be a 55 wedged joint between said two walls, caused by their inclination toward each other and the slight resilience of the sides 11 and 12 and the members 16 and 17, the point of contact being flush with or slightly forward 60 of the rear face of the jamb, making a neatly 65

rounded and wedged tight joint. The inner portion of the said channel engaging the glass, which is flush with or slightly forward of the jamb, is slightly removed from the glass, and has its extremity clenched down upon the glass to form a tight joint to prevent lodgment of mail therein. It will be observed that the wedging pressure is exerted on the glass-holding channel 47 at a point in line with the rear wall of the channel, and the result of the wedging pressure will therefore be a tendency to force laterally or toward each other, the rear walls of the two channels 47 at opposite side edges of the panel 42, and thus said panel 70 edges will be clamped more tightly between the front and the rear walls of the channels 47 as the wedging pressure will force the engaging edges of said rear walls not only laterally, but forwardly, or toward the respective front walls. It will also be noted that there is a free space between the side edge of the glass panel 42 and the rearwardly inclined side wall of the channel 47, so that said side wall can swing laterally to a slight 75 extent, under the influence of the wedging action described above, the forward corner of each channel 47 being in close engagement with the corner of the panel 42, and forming a pivot for such swinging movement. Downwardly and inwardly projecting hooked portions 52 struck from the said strips 43 and 44, are provided in spaced relation along the said panels, and engage 80 cut-out portions 53 provided in the jambs 100 16 and 17, the said cut-out portions being cut from the front faces and outer sides thereof, thereby securing the panels to the said jambs and permitting removal thereof by upward movement of the said panels. 105 The inner faces of the said hooked portions are very slightly beveled, so that there is formed a gradually tightening joint. The upper portion of the frame of the upper panel or front wall comprises a horizontal 110 member 48 of U-shape in cross-section extending around three sides of the panel and secured to the upper end of the members 43 and 44 by means of screws 49, blocks 50 being provided on the said member 48 through 115 which the screws pass. A cut-out portion 51 is provided along the upper portion of the said member 48, so that when the panel is in position, the said member engages the top section 21 and the ends of the same about 120 the molding strips 30 thereof.

The upper portion of the lower panel comprises a strip 54 having its ends inclosing the upper ends of the strips 43 and 44 and secured thereto by means of rivets 55. The upper end of the said strip is bent inwardly upon itself, and its extremity is upset, as at 56, to engage the glass panel, and the lower end of the said strip is bent forwardly, as at 57, to form a horizontal transverse bar. 130

The lower portion of the upper panel is formed in a somewhat similar manner, comprising a strip 58 having its ends inclosing the lower ends of the strips 43 and 44 and secured to the same by rivets 59, the said strip being bent at its lower end upwardly upon itself, inwardly at right angles thereto at 60, and downwardly to form an apron 61, the upper end of the said strip being bent 10 forwardly to form a horizontal transverse bar, a locking device, as hereinafter described, being provided between the two sections engaging the forwardly projecting transverse bars. The lower end of the lower 15 panel comprises a horizontal member 62 secured to the lower ends of the strips 43 and 44 by screws 63, and engages the top of the base 34. A recessed portion 64 is provided at the inner side of the said member, upon 20 which the end of the glass panel is seated, the said panel slightly overhanging the said recess, and a shoulder 65 is provided beneath the recessed portion, which engages the frame 36 and the bent-over portion of the 25 extension 38. A downwardly extending flange 66 is provided extending into the said extension, and an inclined portion 66' is provided between the said flange and the said recessed portion 64 to form an unob- 30 structed passage for the mail.

When the two sections are placed in the proper position, a locking bar 67 is placed at their junction, the said bar comprising upper and lower flanges 68 and 69, which engage the upper and lower faces of the transverse bars of the two sections respectively, and side members 70, recessed portions 71 being provided in the said flanges to enable the said locking bar to be fitted over the 40 jambs at the sides of the panels.

For retaining the said bar in position, bolts 72 and 73 having hooked ends 74 are guided in the member 75, and are adapted to be projected to an outer position and retracted by 45 the operation of the lock 76. The inner faces of the said hooked ends are slightly beveled to make a snugly fitting joint when locked. In the projected or outer position, the hooked portions are disposed in apertures 77 pro- 50 vided in the inwardly projecting members 78 and 79 secured to the sides of the mail chute, and the bar is free to be removed, so that the panels may be lifted out of position, but in the retracted position the said hooked 55 ends engage embossed portions 80 at the sides of the apertures 77, and the locking bar is locked in position, thereby preventing movement of the panels. Inwardly inclined aprons 78' and 79' are provided at the back 60 of the projecting members 78 and 79, over which the apron 61 of the upper front wall fits for forming an unobstructed passage for the mail.

The drop-opening of the chute comprises 65 a hollow member 81 having a flange 82 along

each side, which is engaged by the glass supporting channel 47, and a flange 83 along the lower side engages the front face of the glass. Recesses 84 are provided at the rear of the said opening, into which the plate 70 glass extends, and in which it is supported, and a gate 85 is pivoted at the upper end of the front wall of the said member at 86, flanges 87 being provided at the upper edges of the sides to prevent the said gate from 75 being drawn out of the opening, and projections 88 are provided on the lower side of the gate for supporting the same in inclined position when the said gate is open.

For the purpose of closing the gate when desired, an opening 89 is provided in the same, which may be engaged by a hook or wire from the outside of the chute, without removing panels, for drawing the gate to closed position against the flanges 87, where- 80 upon spring-pressed plungers 90 (Fig. 8) provided at the sides of the drop-opening engage beneath the sides of the said gate, and hold the same in raised position against the flanges 87. By comparatively slight 90 pressure on the said gate, the same may be disengaged from the side walls when desired to open the drop-opening. An inclined guide member 92 is disposed within the opening, being secured at its lower end to 95 the lower inner edges of the member 81, and at its upper end to the front face thereof to guide the mail into the chute.

With my improved invention, a very satisfactory and advantageous mail chute is pro- 100 vided, which is substantial in construction, absolutely free from obstruction to impede or choke the mail dropping therethrough, and quickly opened and closed when de- 105 sired.

I have illustrated and described one embodiment of my invention, but it is obvious that changes may be made therein within the spirit and scope thereof, as defined in the appended claims. 110

I claim:

1. An improved mail chute, comprising a rear wall, side walls bent forwardly therefrom, jambs at the forward ends of said side walls, provided with inclined inner faces, 115 forming an opening of gradually decreasing width at the front of said chute, and front walls engaging the said side walls and adapted to form a frictional yielding contact at one point longitudinally of said inclined inner faces to maintain a tightly closed joint at said point of contact.

2. An improved mail chute, comprising a rear wall, side walls bent forwardly there- 125 from, jambs at the forward ends of said side walls, provided with inclined inner faces forming an opening of gradually decreasing width at the front of said chute, and front walls engaging the said side walls, said edges being inclined in an opposite di- 130

rection from said inclined inner faces of the jambs, and adapted to form a frictional yielding contact at one point longitudinally of said inclined inner faces, to maintain a 5 tightly closed joint at said point of contact.

3. An improved mail chute, comprising a rear wall, side walls bent forwardly therefrom, jambs at the forward ends of said side walls, provided with inclined inner faces 10 forming an opening of gradually decreasing width at the front of said chute, and front walls engaging the said side walls and provided with longitudinal recesses frictionally engaging the said jambs, and adapt- 15 ed to form a frictional yielding contact at one point longitudinally of said inclined inner faces to maintain a tightly closed joint at said point of contact.

4. An improved mail chute, comprising a rear wall, side walls bent forwardly therefrom, jambs at the forward ends of said side walls bent inwardly therefrom, forwardly from the said inwardly bent portion to form inclined inner faces, outwardly therefrom 25 and rearwardly to the said inwardly bent portion to form a longitudinal recess at each side of the said jambs, and front walls provided at each side with longitudinal recesses, frictionally engaging the said jambs.

5. An improved mail chute, comprising a rear wall, side walls bent forwardly therefrom and having a slight resiliency, jambs at the forward ends of said side walls, bent inwardly therefrom, forwardly from the 35 said inwardly bent portion to form inclined inner faces, outwardly therefrom and rearwardly to the said inwardly bent portion to form a longitudinal recess at each side of the said jambs, the said jambs having a 40 slight resiliency and being provided with cut-out portions in spaced relation longitudinally thereof, front walls provided at each side with longitudinal recesses frictionally engaging the said jambs, and hooked portions 45 in the said recesses engaging the said cut-out portions of the jambs.

6. An improved mail chute, comprising a rear wall, side walls bent forwardly therefrom, jambs at the forward ends of said side walls, bent inwardly therefrom, forwardly from the said inwardly bent portion to form inclined inner faces, outwardly therefrom and rearwardly to the said inwardly bent portion to form longitudinal recesses at each 55 side of the said jambs, the said jambs having a slight resiliency and being provided with cut-out portions in spaced relation longitudinally thereof, front walls comprising channel-shaped side members having hooked 60 portions provided in the webs thereof, adapted to engage the cut-out portions of the said jambs, and inwardly extending flange portions, a sheet-metal shell inclosing the said channel and the said flanged portion, and extending upwardly and inwardly 65

therefrom to form with the said flange a channel, a glass panel held at its edges in said channel, the said channel-shaped side members and the said glass engaging channels being adapted to frictionally engage 70 the said jambs.

7. A mail chute comprising a body section having an opening at the front and rearwardly-converging surfaces at the sides of said opening, and a front panel for closing 75 said opening, the sides of said front panel being engaged with friction pressure between said converging surfaces, at the rear surface of said front panel.

8. A mail chute comprising a body section 80 having an opening at the front and jambs at the sides of said opening, and a front panel for closing said opening, the side portions of said panel having their rear surfaces flush with the adjacent rear surfaces 85 of the respective jambs, and immediately contiguous to such surfaces so as to form continuous smooth surfaces therewith, and being in tight engagement with the said jambs.

9. A mail chute comprising a body section having an opening at the front, and a front panel for closing said opening, said panel comprising a pane and side channels embracing the edges of the pane and fitted 95 tightly between the edges of said opening, said channels having front walls engaging the front face of the pane, side walls engaging the side faces of the pane at the forward corners only and diverging therefrom rear- 100 wardly, and rear walls engaging the rear face of the pane.

10. A mail chute comprising a body section having an opening at the front, and a front panel for closing said opening, said panel comprising a pane and side channels embracing the edges of the pane and fitted 105 tightly between the edges of said opening, said channels having front walls engaging the front face of the pane at the side edges 110 thereof, side walls engaging the side faces of the pane at the forward corners only, and rear walls, the main portions of which are out of contact with the pane while their inner edges have a bearing against the rear 115 face of the pane.

11. A mail chute comprising a body section having an opening at the front and rearwardly-converging surfaces at the sides of said opening, and a front panel for closing 120 said opening, having forwardly-converging side surfaces, the rear portions of which engage said rearwardly-converging surfaces of the body section.

12. In a mail chute, a body portion provided with longitudinal jambs having openings, and a panel movable lengthwise of the body portion and provided with longitudinal channeled portions open rearwardly and each straddling or embracing one of said 125 130

jambs, said panel also having, within its channeled portions, hooks adapted to enter said openings.

13. In a mail chute, a body portion having longitudinal jambs, and a panel movable lengthwise of the body portion and having longitudinal channeled portions open rearwardly and each straddling or embracing one of said jambs, said channeled portions and jambs being provided at their adjacent surfaces with mating projections and sockets adapted to be brought to locking or releasing positions by the longitudinal movement of the panel.
14. In a mail chute, a body portion having longitudinal jambs, and a panel having longitudinal channeled members, each open

rearwardly to straddle or embrace one of said jambs, the inner portions of said members being provided, between the jambs, 20 with inwardly-open channels, and a panel whose side edges are fitted into said channels, the body portion and panel having converging resilient walls abutting to form a flush joint when the panel is locked in closed 25 position.

In testimony that I claim the foregoing as my invention I have signed my name in presence of two subscribing witnesses.

FREDERICK B. COOK.
